UNITED STATES PATENT OFFICE.

THOMAS PERCY HALL AND ARTHUR BATES, OF LEICESTER, ENGLAND, ASSIGNORS TO
UNITED SHOE MACHINERY COMPANY, OF PATERSON, NEW JERSEY, A CORPOR-
ATION OF NEW JERSEY.

CEMENTING-MACHINE.

1,191,590.

Specification of Letters Patent. Patented July 18, 1916.

Application filed September 21, 1912. Serial No. 721,658.

To all whom it may concern:

Be it known that we, THOMAS P. HALL and ARTHUR BATES, subjects of the King of England, residing at Leicester, Leicestershire, England, have invented certain Improvements in Cementing-Machines, of which the following description, in connection with the accompanying drawings, is a specification, like reference characters on 10 the drawings indicating like parts in the several figures.

This invention relates to cementing machines and is illustrated in connection with a machine of the type shown in Letters Patent No. 1,030,273 for applying a band of cement to a piece of leather.

It is desirable in machines for applying a band of cement to a piece of stock that provision be made for varying the width of the 20 band.

Accordingly one feature of the present invention consists of the combination with a cement applying member of means for varying the effective surface of said member; and in the illustrative machine an adjustable shield is arranged for movement 25 across the surface of the cement applying member.

In machines of this class a presser is commonly provided which holds the stock against the cement applying member, the presser and applying member coöperating to feed the stock. In a construction such as that shown in the patent referred to above, 30 wherein the two members between which the stock is fed occupy fixed positions with respect to each other, the band of cement is always applied to approximately the same locality on every piece of stock. It is desirable, however, that the location of the band be under control.

Another feature of the invention, then, 45 consists of the combination of a plurality of members between which the stock is fed and means for causing relative movement of said members to grip the stock between them, one of said members being adjustable longitudinally of the other. Besides the advantage which such relative adjustment 50 gives in locating the band of cement close to or spaced from the margin of the stock it should be noted that it also permits the presser to be brought into register with the exposed surface of the applying roll where

said roll is provided with a shield for controlling the width of the band of cement.

These and other features of the invention, including certain details of construction and combinations of parts, will be described in connection with an illustrative machine and 60 pointed out in the appended claims.

Figure 1 is a side elevation of an illustrative machine with a portion broken away and other parts in section to show clearly the construction of the machine; Fig. 2 is a 65 plan of the machine shown in Fig. 1 with the spring 69 and certain parts above the work table removed; Fig. 3 is a view drawn to a larger scale than the preceding figures, showing in detail the cement-distributing 70 and work-pressing devices, and Fig. 4 is a view from the rear of the machine, also with parts in section.

The cementing machine with which the invention is described as associated is of the 75 same general type as the machine described in the said prior patent and comprises a closed trough or tank 1 for containing the cement. Projecting through an opening in the upper plate 3 of the tank, which forms 80 the work table, is a cement applying roll 5 the surface of which is provided with indentations and by the rotation of which the cement is brought into contact with the work, the work being maintained in contact 85 with the said roll by an overhead presser roll 7. The presser roll 7 and cement applying roll 5 are rotated through mechanism hereinafter described from a shaft 9 driven from an external source of power.

In this embodiment of the invention the cement applying roll 5 does not dip into the cement as in the machine of the prior patent but it is arranged to bear against a frusto-conical supply roll 11 which is mounted so 95 as to extend into the cement and thus supply the cement applying roll 5 with cement as the latter is rotated, the frusto-conical roll being revolved frictionally by contact therewith. The frusto-conical supply roll 11 is 100 mounted upon a stud or spindle 13 projecting inwardly from the wall of the trough 1, the stud or spindle being secured to the wall at such an angle as to maintain the upper part of the conical surface of the roll 11 in 105 parallel relationship with the lower surface of the cement applying roll 5. Within the stud 11 a spring 15 is arranged which by

bearing on the said roll or on an intermediate member such as the plunger 17 tends to press it yieldingly into contact with the cement applying roll 5. The provision of this auxiliary spring-pressed supply roll 11 insures that the cement is supplied to the cement roll in a more regular manner and with greater certainty than has previously been possible.

10 The cement applying roll 5 is made of considerably greater width than the roll in the machine of the said prior patent, and a shield 19 is employed that is adjustable in a direction parallel with the axis of the roll, 15 so that any desired amount of the surface not required for use may be masked or covered over. The shield 19 conveniently may be formed as a plate adapted to slide on the table, the plate having a portion 21 (see 20 Fig. 3) shaped to conform closely to the projecting portion of the roll 5. Conveniently, the sliding plate 19 forms a support for an edge gage 23 which may be employed to guide the work, the said gage being adjustably secured to the plate. Conveniently, 25 the gage 23 may be pivoted, as shown at 25, Fig. 2, to the plate 3 so that it can be turned out of the way of the work when it is desired to apply cement to the central portion 30 of the work.

The means for adjusting the shield 19 backwardly or forwardly over the cement roll 5 may comprise, according to this embodiment of the invention, a hand lever 27 pivoted at 29 upon the table or plate 3 of the tank 1, the said lever being connected with the shield by a link 31. By the operation of the hand lever 27 the sliding plate 19 is moved to cover more or less of the roll 5 40 whereby the effective surface of said roll will be lessened or increased, and a wider or narrower edging of cement thereby be applied to the work.

As before stated, an overhead roll 7 is employed to coöperate with the cement applying roll 5, the overhead roll being mounted in an overhanging arm 33 that is fulcrumed upon the shaft 9 mounted in bearings on the casing of the trough 1 in such a manner that 50 the overhead feed roll 7 may be brought down into contact with the work on the roll 5 by a connection from a treadle as herein-after described. The overhead roll 7 is narrow as compared with the width of the roll 5 and is adjustable along a line parallel with the axis of said roll so as to act on the edge of the work notwithstanding the width of the edging of cement being applied, or to act upon a line the distance of which from 55 the edge may be varied according to requirements. This adjustability of the roll 7 may be secured by mounting it upon the shaft 35 by which it is rotated in such manner that it can slide thereon and providing it with a 60 groove 37 with which a yoke piece 39 en-

gages. The yoke piece is attached to a screw 41 which passes through bearings 43 projecting upwardly from the overhanging arm 33 in which the shaft 35 carrying the roll 7 is mounted. A nut 45 threaded on the screw 41 is placed between the bearings 43 so that by turning the same the yoke piece 39 will cause the upper roll 7 to be traversed to the position desired in relationship to the edge gage 23 or to the effective portion of the surface of the cement applying roll. The yoke piece 39 may also be formed with a recess 47 in which is fitted a cleaning pad 49 that wipes off any cement that may be on the overhead roll.

The driving mechanism by which the various parts of the machine are operated is, as before suggested, treadle controlled and may conveniently be arranged as follows:— The shaft 9 upon which the overhang arm 33 hereinbefore referred to is centered constitutes the driving shaft of the machine and is provided with a loose and a fast pulley 51, 53 by which latter power may be applied from an external force to the machine. On the driving shaft 9 is a worm 55 that gears with two worm wheels one wheel 57 being mounted on the shaft 59 carrying the cement applying roll 5 and the other wheel 61 being on the shaft 35 carrying the overhead roll 7. By this arrangement of the parts the overhanging arm 33 can be turned on the driving shaft 9 to raise the overhead roll 7 from the work without disconnection of the worm gear by which said roll is driven.

To transfer the belt from the fast to the loose pulley and vice versa a belt shifter 65 is employed, the same being mounted on a rod 67 that is adapted to slide in bearings on the machine frame, and is normally maintained by a spring 69 in a position in which the belt is on the loose pulley 51.

To operate the slide rod 67 from a treadle in opposition to the spring a bell-crank lever 71 is employed, which lever is fulcrumed on the machine frame with one arm connected by a chain 73 or the like with the treadle (not shown) and the other arm projecting into a recess in the slide rod 67. By this arrangement when the treadle is depressed the bell-crank lever 71 will slide the rod 67 in its bearings and transfer the belt from the loose pulley 51 to the fast pulley 53 and thereby start the machine so that both the cement applying roll and the presser roll 130 will be rotated and the work supplied with cement and moved along past the edge gage.

The overhanging arm 33 which, as aforesaid, is centered on the driving shaft 9, is acted upon by a spring 75 or it may be so balanced as to raise the overhead roll 7 normally from off the work when the belt is on the loose pulley. Mechanism, however, is provided to press the overhead roll 7 down upon the work when the belt is transferred 135 140

from the loose to the fast pulley. For this purpose a wedge block 77 is provided on the slide rod 67 aforesaid which wedge block is so arranged that when the slide rod is moved 5 to bring the belt on to the fast pulley 53 the wedge will engage an abutment 79 carried in the end of the overhead swinging frame whereby the said frame will be turned on the driving shaft 9 and the roll 7 pressed 10 against the work. The pressure of the roll upon the work is exerted yieldingly, and for this purpose the abutment 79 is acted upon by a spring 81 that surrounds a stem 89 forming part of the abutment. The stem 15 89 is screw-threaded, and nuts 91 screwed on the stem and bearing on the swinging frame provide means for adjusting the extent of yield of the abutment and the consequent amount of pressure with which the 20 roll 7 is pressed against the work. The adjustment of pressure upon the work can thus be regulated according to requirements.

Similar to the machine described in the said prior patent the machine of the present application is provided with a pair of strippers or scrapers 93 which are employed in the operation of the machine to regulate the supply of cement to the roll 5 during the operation of the machine and are used 25 to close, when the machine is at rest, the opening in the plate through which the cement applying roll projects. The said strippers comprise two levers of the first order centered upon the under surface of the table 30 of the trough. The levers are so shaped at their ends adjacent to the cement applying roll 5 as to close against the periphery of the same. The said portions tend to close and are kept in place by a compression 35 spring 95 placed between the other ends of the levers. Projections 97 from the levers are arranged to coöperate with one another so as to cause them to move together when one of the said levers is operated, and to 40 enable this to be done an extension 99 from one of the levers is provided which is engaged by a push rod 101 that is carried by an arm 103 projecting from the slide bar 67 hereinbefore mentioned.

50 The push rod 101 is adjustable longitudinally by means of a portion which is screw threaded in a boss of the arm 103 aforesaid so that the extent to which the strippers 93 are moved from the roll 5 in the operation 55 of the machine can be varied according to requirements. The push rod is secured in adjusted position by a nut 105 screwed upon the threaded portion. It will thus be seen that when the slide rod 67 has been 60 moved to transfer the belt from the loose pulley 51 to the fast pulley 53 and lower the roll 7 on to the work, the strippers 93 will be moved away from the roll 5 by the push rod 101 engaging the extension 99 of 65 the stripper lever, the other stripper lever

being at the same time actuated through the coöperating projections 97.

The operation of the machine as a whole briefly stated is as follows:— When the operator depresses the treadle the slide rod 67 70 is moved in opposition to its spring 69 by the bell crank lever 71. This movement of the slide rod 67 affects three mechanisms of the machine, first, it moves the belt from the loose pulley 51 to the fast pulley 53 and 75 thereby drives through the worm gearing 55, 57, 61 the coöperating cement applying roll 5 and overhead roll 7; secondly, the overhead roll 7 is brought down yieldingly into contact with the work by the wedge 77 80 85 89 on the slide rod 67 engaging the yielding abutment 79 on the end of the overhanging arm 33; and thirdly, the strippers 93 are moved away from the roll 5 to an amount predetermined by the adjustment of the push rod 101 to regulate the amount of cement applied to the work.

Previous to the operation of the machine as above described, the operator will have adjusted the shield 19 by the operation of 90 the hand lever 27 to the extent necessary to provide the desired width of cement, and at the same time the overhead roll 7 will have been adjusted by the screw nut 45 to bear upon the work at the desired place. 95

Although the invention has been set forth in connection with a particular machine it should be understood that the invention is not limited in the scope of its application to the particular machine shown and described. 100

Having thus described our invention, what we claim and desire to secure by Letters Patent of the United States is:

1. A machine of the class described having, in combination, a comparatively wide, cement applying roll, a narrow presser member arranged to hold the work against said roll, and means whereby said presser member may be adjusted to coöperate with any 105 selected zone of the applying roll.

2. A machine of the class described having, in combination, a comparatively wide, cement applying roll, a narrow presser roll arranged to hold the work against said applying roll, a rotary shaft to which said presser roll is keyed, and means for adjusting said presser roll along said shaft to cause it to coöperate with any selected zone of the 115 applying roll.

3. A machine of the class described having, in combination, a member for applying cement to a piece of stock, means for operating said member, and a shield extending partially over said member from one end 120 thereof and adjustable across said member to vary its effective surface.

4. A machine of the class described, having, in combination, a roll for applying cement to a piece of stock, means for rotating 125

said roll, a shield extending partly over said roll from one end thereof and adjustable longitudinally thereof to vary the exposed area of said roll, a narrow presser roll, and 5 means whereby said presser roll may be adjusted to coöperate with any selected zone of said applying roll.

5. A machine of the class described having, in combination, a member for applying 10 cement to a piece of stock, a shield extending partially over said member from one end thereof and adjustable across said member to vary the width of the band of cement applied to the stock, and an edge gage 15 mounted upon said shield.

6. A machine of the class described having, in combination, a member for applying cement to a piece of stock, a shield extending partially over said member from one end 20 thereof and adjustable across said member to vary the width of the band of cement applied to the stock, and an edge gage adjustably mounted upon said shield.

7. A machine of the class described having, in combination, a member for applying cement to a piece of stock, a shield extending partially over said member from one end thereof and adjustable across said member to vary the width of the band of cement applied, and an edge gage for guiding the stock so that the band of cement is applied to the margin of said stock, said gage being movable to one side to permit a band of cement to be applied to the stock at a distance from 35 the margin thereof.

8. A machine of the class described having, in combination, a cement applying roll, a presser member for holding the stock in contact therewith, a frusto-conical roll for 40 supplying cement to the applying roll, and a spring acting to move said applying roll in the direction of the axis thereof to hold said roll in contact with the applying roll.

9. A machine of the class described having, in combination, a reservoir provided 45 with an opening, a cement applying member arranged to receive cement from said reservoir, means for applying power to said member, automatic means becoming operative 50 upon the withdrawal of said power for closing said opening, and a presser member, one of said members being adjustable longitudinally of the other.

10. A machine of the class described having, in combination, a reservoir, a cement 55 applying member, a presser for coöperating

with said member to feed the work, a single member movable to cause successively actuation of said applying member and movement of said presser into engagement with 60 the work, an adjustable shield for varying the effective surface of said applying member, and means for adjusting said presser in a direction parallel with the movement of adjustment of said shield. 65

11. A machine of the class described having, in combination, a reservoir, a cement applying member, a presser for coöperating with said member to feed the work, and a single member movable to cause successively 70 actuation of said applying member and a movement of said presser into engagement with the work, said presser being adjustable across the face of said applying member.

12. A machine of the class described having, in combination, a reservoir, a cement applying member, means for actuating said member, sealing means for said reservoir, a presser adjustable across the face of said cement applying member, and a single member 75 for opening said sealing means and for moving said presser to operative position. 80

13. A machine of the class described having, in combination, a reservoir for cement, a cement applying roll arranged to receive 85 cement from said reservoir, a presser roll located above said cement applying roll, a receptacle through the bottom of which the upper portion of the presser roll projects, and a wiping member located in said receptacle in contact with the presser roll. 90

14. A machine of the class described having, in combination, a reservoir for cement, a cement applying roll arranged to receive cement from said reservoir, a presser roll 95 located above said cement applying roll, a receptacle through the bottom of which the upper portion of the presser roll projects, a wiping member located in said receptacle in contact with the presser roll, and means for 100 simultaneously adjusting said presser roll and receptacle in a direction parallel to the axis of said roll.

In testimony whereof we have signed our names to this specification in the presence 105 of two subscribing witnesses.
